DESIGN FOR A GRILLE GUARD

Gustave F. Bahr, Bridgeport, Conn., assignor to Casco Products Corporation, Bridgeport, Conn.,
a corporation of Connecticut

Application October 28, 1939, Serial No. 87,900

Term of patent 14 years

To all whom it may concern:

Be it known that I, Gustave F. Bahr, a citizen of the United States, residing at Bridgeport, in the county of Fairfield and State of Connecticut, have invented a new, original, and ornamental Design for a Grille Guard, of which the following is a specification, reference being had to the drawing, forming part thereof.

Fig. 2 is a side elevational view of a grille guard, showing my new design.

Fig. 3 is a top elevational view of a grille guard, showing my new design.

I claim:

The ornamental design for a grille guard, as shown.

GUSTAVE F. BAHR.
